UNITED STATES PATENT OFFICE.

LOUIS JOHN LE MESURIER, OF NEWCASTLE-UPON-TYNE, ENGLAND, ASSIGNEE OF
ONE-HALF TO SIR W. G. ARMSTRONG WHITWORTH & COMPANY LIMITED, OF
ELSWICK WORKS, NEWCASTLE-UPON-TYNE, ENGLAND.

AEROPLANE-ARRESTING APPARATUS.

1,315,320.

Specification of Letters Patent. Patented Sept. 9, 1919.

Application filed June 10, 1919. Serial No. 303,059.

To all whom it may concern:

Be it known that I, LOUIS JOHN LE MESURIER, a subject of the King of England, and resident of Newcastle-upon-Tyne, 5 Northumberland, England, have invented certain new and useful Improvements in Aeroplane-Arresting Apparatus, of which the following is a specification:

This invention relates to apparatus for 10 the arresting of aeroplanes and has for its object to enable an aeroplane to land in a comparatively confined space as for example on a ship's deck.

In order to enable an aeroplane to land 15 safely on a ship several important points have to be taken into consideration. In the first place the aeroplane must be piloted with accuracy into the space in question and the direction in which the aeroplane is moving when the landing is effected must be defined within reasonable limits. The extent 20 of the area necessary for landing will be governed largely with the accuracy which it is possible to attain in these respects naturally taken in conjunction with the weather 25 conditions. Assuming that a given area has been determined within which a machine can safely be expected to alight at flying speed then it should be possible by means 30 of a suitable device to restrict considerably the additional area which in ordinary conditions is required to allow of the machine being safely brought to rest. By means of the present invention the movement of the 35 aeroplane is arrested on landing within a given area while means are provided for holding down the aeroplane when it has come to rest. The latter is a feature of importance as it is possible that when a machine 40 has landed and come to rest it may be subjected to wind currents or eddies which will displace the machine before it can be secured. For instance if the ship on which the landing is effected is steaming in 45 the direction in which the aeroplane lands some means must be provided to prevent the aeroplane from being blown backward as soon as it has come to rest relatively to the deck of the ship.

According to this invention one or more 50 flexible loops are disposed at or toward one end of a rope whose other end is in sliding engagement with the loops on the first end

or with the part of the rope adjacent to each loop.

55

The rope is led around two pulleys which are spaced apart and the aeroplane is provided with means by which when it is alighting it can engage a loop so that the aeroplane can be arrested and held down 60 by the rope. The loops are arranged to pass through eyes mounted on or toward the other end of the rope. Thus the loops on one end of the rope are engaged by and can slide through the eyes on the other end 65 of the rope. The pulleys are so arranged as to be relatively movable in order to increase the distance between them and thereby exert a pull on the rope so as to cause the eyes to slide along the loops. The aeroplane is 70 provided with a hook or the like by means of which a loop is engaged when the aeroplane is effecting a landing and the arresting and holding down of the aeroplane is then accomplished by forces applied to the 75 aeroplane through the rope. For convenience of reference the loops may be termed "aeroplane-engaging loops" and are so referred to in the claims and it is to be understood that the term covers a loop adapted 80 to be engaged by a hook or like member connected to or forming part of the aeroplane. The arresting is effected by applying a resistance which is either cumulative or otherwise to the travel of the rope over 85 or around the pulleys. The holding down is accomplished by a pull on the loop when it is engaged by the hook on the aeroplane this pull being brought about by the relative movement of the pulleys around which 90 the rope passes. Thus the aeroplane will not be subjected to any undue shock when it engages a loop since the masses are relatively small that are then suddenly put into motion namely the loop which is straightened out and the rope which is caused to travel around the pulleys.

95

The invention may be put into practice in various ways and the accompanying drawings illustrate by way of example constructions that may conveniently be employed. In these drawings:

100

Figure 1 is a plan of the apparatus showing the arrangement of the ropes and loops;

Fig. 2 is a somewhat diagrammatic side 105 elevation showing the manner in which the

loops are engaged by an aeroplane when alighting;

Fig. 3 is a perspective view illustrating the way in which the loops are disposed and held in position;

Fig. 4 is a vertical sectional elevation showing a rope and a loop and the means by which the aeroplane is arrested and held down after engaging the loop;

Fig. 4^a is a detail view on an enlarged scale showing means for automatically moving one pulley away from the other;

Fig. 5 is a side elevation on an enlarged scale of one of the springs employed for holding the loops;

Fig. 6 is a side elevation illustrative of one method of holding and guiding a traveling rope on the landing surface;

Fig. 7 is a plan of the same;

Fig. 8 is a section on the line 8—8 of Fig. 6;

Fig. 9 is a plan of a shock absorbing device as it may be employed.

Like letters indicate like parts throughout the drawings.

On the deck A of a ship or other landing place selected a wire or other light rope B is disposed at or toward one end of which are formed or attached a series of flexible aeroplane engaging loops B' formed for example of wire rope. The rope B is arranged in the direction in which landing is to be effected that is to say fore and aft in the case of a ship's deck. Each of the loops B' is on a separate pendant or part B² attached to the main part of the rope so that the loops can be arranged along the deck in a row one behind the other along the rope B which extends beneath all the loops as shown in Fig. 1. The rope is carried around two pulleys C and C' suitably spaced apart as shown in Figs. 1 and 4 and mounted on horizontal spindles and the end of the rope opposite to that which carries the loops B' is provided with a series of eyes B³ through each of which passes a pendant part B² which carries the loop B' at the first end of the rope. The arrangement is such that if a pull is exerted on the rope B the ends thereof will move in opposite directions and each loop B' will tend to be drawn through an eye B³. Each loop B' is opened out and arranged in a flattened form as shown in Figs. 1 and 3 so as to lie across the rope B with the part B⁴ of the loop on or below the landing surface A while the other part B' is held a short distance above this surface conveniently by means of a series of light springs D attached to the landing surface. Thus when an aeroplane E is about to alight as it comes down on the landing surface A it will pass as shown in Fig. 2 in succession over these loops and a hook F suitably disposed on the under part of the aeroplane will engage

with certainty one or other of the loops. Conveniently two or more ropes B are arranged parallel to each other as shown in Fig. 1 each rope being carried around a pair of pulleys C C' while the loops B' on these ropes are disposed side by side or so as to alternate as found desirable. In this way a number of loops can be distributed over the area on which the aeroplane alights and so as to insure that wherever the aeroplane comes down in this area the hook F thereon will engage a loop. By employing springs such as D to hold the loops B' open or spread them no interference will be offered to the travel of the aeroplane over the landing surface since the loops are flexible and the springs will yield as the landing wheels of the aeroplane pass over them in the manner indicated in Fig. 2. Each rope B with its series of loops B' may be regarded as a complete element and each element is preferably arranged and controlled independently of the others. The number of elements employed and their relative disposition will be determined by the area of the landing space available.

When an aeroplane alights and engages one of the loops B' the latter will be drawn out of the supporting spring clips D and pulled from a transverse into a longitudinal position. The rope B which carries the loops will then travel around the pulley C C'. The process of picking up and straightening out a loop formed of a light steel wire will not subject the hook on the aeroplane to any undue shock or strain. Similarly it is possible to reduce the mass of the rope element so as to prevent any serious shock when it is put into motion. If desired however some convenient form of shock absorber such as a spring G can be introduced at a suitable point in the rope as illustrated in Fig. 9. Resistance to the movement of the rope B is offered preferably by carrying that part of the rope which lies beneath the landing surface through a tube or cylinder H of suitable length in which is a piston H' attached to the rope as shown in Fig. 4. Resistance to the travel of the piston along the cylinder is offered preferably by the air pressure on one face of the piston and the vacuum which tends to be created at the other side of the piston. Suitably controlled openings for the escape and inlet of the air at the opposite ends of the cylinder H may be provided. The length of the cylinder H and the stroke of the piston H' therein is determined with relation to the type of aeroplane with which the apparatus is to be used and the arresting force and travel suitable both to the aeroplane and the landing conditions. Alternatively a frictional device of some suitable type may be employed and applied to the longitudinal part of the rope B so as to subject the aeroplane

as it alights to the necessary predetermined and if desired cumulative arresting force.

One of the pulleys around which the rope B passes and preferably that one C which is most remote from the end of the alighting area which the aeroplane first approaches, is mounted so as to be movable away from the other pulley C'. Conveniently this pulley C is mounted on a rod C² 10 and connected to a piston movable in a cylinder C³ to which air or liquid under pressure can be delivered, this arrangement being illustrated in Fig. 4. Fig. 4^a illustrates diagrammatically an arrangement 15 whereby the pulley C is automatically moved after the rope has traveled a predetermined distance. This arrangement comprises a lever C⁴ connected to the spindle of the valve controlling the admission of fluid pressure— 20 e. g. compressed air—to the cylinder C³. This lever is controlled by a spring C⁵ and normally held in the position shown by a trigger C⁶ connected to one arm of a bell crank lever C⁷. The other arm of the bell 25 crank lever C⁷ is adapted to be engaged by a collar or projection B⁶ secured to the rope B, so that when the rope has traveled a predetermined distance over the pulley C the collar will actuate the bell crank lever C⁷ thus 30 releasing the trigger C⁶ and admitting compressed air to the cylinder whereupon the piston rod C² is forced outward and the pulley C moved away from the other pulley C' thus exerting a pull on the rope B and each 35 of the loops B' at one end of the rope will tend to be drawn through the corresponding eye B³ on the other end of the rope. This will have the effect of holding down the aeroplane after its horizontal motion has 40 been arrested the movement of the pulley preferably commencing before the arresting of the aeroplane is complete. The movement of the pulley C is preferably caused to commence automatically when or shortly 45 after the hook F on the aeroplane E has engaged one of the loops B'. This may be effected by means of suitable mechanism actuated by the pull on the rope B so as to admit air or liquid under pressure to the 50 cylinder C³ in which is the piston connected to the movable pulley C.

The supports by means of which each loop B' is maintained in the opened out state may each comprise a spring strip D rigidly attached at one end to the deck or other landing surface A while the free end curves upward as shown in Fig. 5 and is provided with a spring clip D' in which the loop B' rests and from which it can be easily withdrawn when picked up by the hook F on the aeroplane.

The hook F is attached to the aeroplane at a point which is as near as possible to the center of gravity of the machine so as to 65 minimize the tendency of the machine to

tip when being arrested. The hook F as shown in Fig. 2 is preferably carried on the end of an arm F' pivoted beneath the fuselage and means are provided such as a cord F² for lifting the hook when not required and for lowering it into an operative position when landing.

The rope B is preferably guided along the alighting surface A and means provided to prevent the hook F from lifting the rods clear of the surface at any time. This may be found necessary particularly when the aeroplane is being held down. For example as shown in Figs. 6, 7 and 8 a guide rail J is secured to the deck or landing surface A and upon this rail runs a shoe K which may also form or have attached to it a ring or eye K' through which the pendant B² which carries the loop B' at the other end of the rope B is threaded. Such a shoe is arranged adjacent to each loop.

If a shock absorber is employed this may comprise as shown in Fig. 9 a coiled spring G interposed between the piston H' in the cylinder H which serves to arrest the travel of the rope B and an adjacent part of the latter. Rope connections B⁵ between these parts are also provided to limit the extension of the spring G.

The details of construction may be modified as required.

What I claim as my invention and desire to secure by Letters Patent is:

1. In apparatus for arresting aeroplanes, the combination of a rope, a flexible aeroplane-engaging loop at one end of this rope, a sliding connection between the second end of the rope and the first end adjacent to the flexible loop and two pulleys spaced apart around which the rope is led and can travel as set forth.

2. In apparatus for arresting aeroplanes, the combination of a rope, a flexible aeroplane engaging loop at one end of this rope, a sliding connection between the second end of the rope and the first end adjacent to the flexible loop, two pulleys spaced apart around which the rope is led and can travel and means for moving the pulleys apart whereby a pull is exerted on the rope as set forth.

3. In apparatus for arresting aeroplanes, the combination of a rope, a flexible aeroplane-engaging loop at one end of this rope, a sliding connection between the second end of the rope and the first end adjacent to the flexible loop, two pulleys spaced apart around which the rope is led and can travel and means for applying resistance to the travel of the rope over the pulleys.

4. In apparatus for arresting aeroplanes, the combination of a rope, a flexible aeroplane-engaging loop at one end of this rope, a sliding connection between the second end of the rope and the first end adjacent to the

flexible loop, two pulleys spaced apart around which the rope is led and can travel, means for moving the pulleys apart whereby a pull is exerted on the rope and means 5 for applying resistance to the travel of the rope over the pulleys.

5. In apparatus for arresting aeroplanes, the combination of a rope, a plurality of flexible aeroplane-engaging loops disposed 10 toward one end of this rope, a plurality of sliding connections between the second end portion of the rope and the first end portion adjacent to each flexible loop and two pulleys spaced apart and around which the 15 rope is led and can travel as set forth.

6. In apparatus for arresting aeroplanes the combination of a rope, a plurality of flexible aeroplane-engaging loops disposed 20 toward one end of this rope, means for normally supporting each loop in a raised position and extending it at right angles to the length of the rope, a plurality of sliding connections between the second end portion of the rope and the first end portion adjacent to each flexible loop and two pulleys 25 spaced apart and around which the rope is led and can travel as set forth.

7. In apparatus for arresting aeroplanes the combination of a plurality of ropes disposed 30 parallel to each other, a flexible aeroplane-engaging loop at one end of each rope, a sliding connection between the second end portion of each rope and the first end portion adjacent to the flexible loop and pulleys 35 spaced apart around which each rope is led and can travel.

8. In apparatus for arresting aeroplanes the combination of a plurality of ropes arranged 40 parallel to each other, a plurality of flexible aeroplane-engaging loops disposed toward one end of each rope, a plurality of sliding connections between the second end portion of each rope and the first end portion adjacent to each flexible 45 loop, a plurality of flexible arms normally supporting each loop in a raised position and extending it at right angles to the length of its rope and pulleys spaced apart around which each rope is led and can 50 travel.

9. In apparatus for arresting aeroplanes the combination of a rope, a plurality of flexible aeroplane-engaging loops at one end 55 of this rope, a sliding connection between the second end of the rope and the first end adjacent to each flexible loop, two pulleys spaced apart around which the rope is led and can travel, means for moving the pulleys relatively to each other so as to exert 60 a pull on the rope and means for applying resistance to the travel of the rope over the pulleys as set forth.

10. In apparatus for arresting aeroplanes the combination of a plurality of ropes, a 65 plurality of flexible aeroplane-engaging

loops disposed toward one end of each rope, means for normally supporting each rope in a raised position and extending it at right angles to the length of the rope, a plurality of sliding connections between the second 70 end portion of each rope and the first end portion thereof adjacent to each flexible loop, two pulleys spaced apart around which each rope is led and can travel, means for moving one pulley in each pair relatively to 75 the other so as to exert a pull on their respective ropes and means for applying resistance to the travel of each rope over its respective pulleys.

11. In apparatus for arresting aeroplanes 80 the combination of a rope, a flexible aeroplane-engaging loop at one end of this rope, a sliding connection between the second end of the rope and the first end adjacent to the flexible loop, two pulleys spaced apart around 85 which the rope is led and can travel and means automatically actuated by the travel of the rope over the pulleys to move the pulleys apart and thus exert a pull on the rope.

12. In apparatus for arresting aeroplanes 90 the combination of a rope, a flexible aeroplane-engaging loop at one end of this rope, a sliding connection between the second end of the rope and the first end adjacent to the flexible loop, two pulleys spaced apart 95 around which the rope is led and can travel and means for moving one pulley relatively to the other comprising a cylinder and a piston, adapted to reciprocate therein under the action of a fluid pressure medium, and 100 connected to one of the pulleys.

13. In apparatus for arresting aeroplanes the combination of a rope, a flexible aeroplane-engaging loop at one end of this rope, a sliding connection between the second end 105 of the rope and the first end adjacent to the flexible loop, two pulleys spaced apart around which the rope is led and can travel and means for applying a cumulative resistance to the travel of the rope over the pulleys as set forth.

14. In apparatus for arresting aeroplanes the combination of a rope, a flexible aeroplane-engaging loop at one end of this rope, a sliding connection between the second end 115 of the rope and the first end adjacent to the flexible loop, two pulleys spaced apart around which the rope is led and can travel, means for applying a cumulative resistance to the travel of the rope over the pulleys and 120 a shock absorbing device between the flexible loop and the resistance mechanism.

15. In apparatus for arresting aeroplanes the combination of a rope, a flexible aeroplane-engaging loop at one end of this rope, 125 a sliding connection between the second end of this rope and the first end adjacent to the flexible loop, two pulleys spaced apart around which the rope is led and can travel and means for applying resistance to the 130

- travel of the rope over the pulleys comprising a cylinder through which a portion of the rope passes and a piston mounted on the rope reciprocating therein.
- 5 16. In apparatus for arresting aeroplanes the combination of a rope, a flexible aeroplane-engaging loop at one end of this rope, a sliding connection between the second end of the rope and the first end adjacent to the flexible loop, two pulleys spaced apart around which the rope is led and can travel, means for applying resistance to the travel of the rope over the pulleys comprising a cylinder through which a portion of the rope passes, a piston mounted on the rope and reciprocating therein, and a shock absorber provided in the length of the rope between the loop and resistance piston. 70
- 10 17. In apparatus for arresting aeroplanes the combination of a rope, a flexible aeroplane-engaging loop at one end of this rope, a sliding connection between the second end of the rope and the first end adjacent to the flexible loop, two pulleys spaced apart around which the rope is led and can travel, means for moving one pulley relatively to the other so as to tend to draw the loop on one end of the rope through the sliding connection on the other end thereof, such means 80 comprising a cylinder and a piston reciprocating therein under the action of a fluid pressure medium and connected to one of the pulleys, means for applying resistance to the travel of the rope around the pulleys comprising a closed cylinder through which a portion of the rope passes and a piston secured to the rope reciprocating within the cylinder. 85
- 15 18. In apparatus for arresting aeroplanes the combination of a rope, a flexible aeroplane-engaging loop at one end of this rope, a sliding connection between the second end of the rope and the first end adjacent to the flexible loop, two pulleys spaced apart around which the rope is led and can travel, means for moving one pulley relatively to the other so as to exert a pull on the rope and tend to draw the loop on one end of the rope through the sliding connection on the other end thereof and means for applying resistance to the travel of the rope over the pulleys comprising a closed cylinder through which the rope passes and a piston secured to the rope and reciprocating within the cylinder. 90
- 20 19. In apparatus for arresting aeroplanes the combination of a rope, a flexible aeroplane-engaging loop at one end of this rope, a sliding connection between the second end of the rope and the first end adjacent to the flexible loop, two pulleys spaced apart around which the rope is led and can travel, means for moving one pulley relatively to the other so as to exert a pull on the rope and tend to draw the loop on one end of the rope through the sliding connection on the other end thereof and means for applying resistance to the travel of the rope over the pulleys comprising a closed cylinder through which the rope passes and a piston secured to the rope and reciprocating within the cylinder. 95
- 25 20. In apparatus for arresting aeroplanes the combination of a rope, a flexible aeroplane-engaging loop at one end of this rope, a sliding connection between the second end of the rope and the first end adjacent to the flexible loop, two pulleys spaced apart around which the rope is led and can travel, means for moving one pulley relatively to the other so as to tend to draw the loop on one end of the rope through the sliding connection on the other end thereof, such means 100 comprising a cylinder and a piston reciprocating therein under the action of a fluid pressure medium and connected to one of the pulleys, means for applying resistance to the travel of the rope around the pulleys comprising a closed cylinder through which a portion of the rope passes and a piston secured to the rope reciprocating within the cylinder, and a shock absorbing device arranged in the length of the rope between the loop and resistance piston. 105
- 30 21. In apparatus for arresting aeroplanes the combination of a rope, a plurality of flexible aeroplane-engaging loops disposed toward one end of this rope, a plurality of sliding connections between the second end portion of the rope and the first end portion adjacent to each flexible loop, a plurality of flexible arms normally supporting each loop in a raised position and adapted to extend each loop at right angles to the length of the rope, two pulleys spaced apart and around which the rope is led and can travel, means for applying resistance to the travel of the rope around the pulleys comprising a closed cylinder through which a portion of the rope passes and a piston secured to the rope and reciprocating within the cylinder and means for moving one pulley relatively to the other so as to exert a pull on the loop which has 110 been engaged by a portion of the aeroplane and so hold down the aeroplane. 115
- 35 22. In an apparatus for arresting aeroplanes, the combination of a rope, a plurality of flexible aeroplane-engaging loops disposed toward one end of this rope, a plurality of sliding connections between the second end portion of the rope and the first end portion adjacent to each flexible loop, a plurality of flexible arms normally supporting each loop in a raised position and adapted to extend each loop at right angles to the length of the rope, two pulleys spaced apart around which the rope is led and can travel, means for moving one pulley rela- 120

tively to the other so as to tend to draw the loop on one end of the rope after it has been engaged by a portion of the aeroplane through the sliding connection on the other end of the rope such means comprising a cylinder and a piston reciprocating therein under the action of a fluid pressure medium and connected to one of the pulleys and means for applying resistance to the travel of the rope around the pulleys comprising a closed cylinder through which a portion of the rope passes and a piston secured to the rope and reciprocating within the cylinder.

23. In apparatus for arresting aeroplanes the combination of a rope, a plurality of flexible aeroplane-engaging loops disposed toward one end of the rope, a plurality of sliding connections between the second end portion of the rope and the first end portion adjacent to each flexible loop, a plurality of flexible arms normally supporting each loop in a raised position and adapted to extend each loop at right angles to the length of the rope, two pulleys spaced apart around which the rope is led and can travel, means for moving one pulley relatively to the other so as to tend to draw the loop on one end of the rope after it has been engaged by a portion of the aeroplane through the sliding connection on the other end of the rope, such means comprising a cylinder and a piston reciprocating therein under the action of a fluid pressure medium and connected to one of the pulleys, means for applying resistance to the travel of the rope around the

pulleys comprising a closed cylinder through which a portion of the rope passes and a piston secured to the rope and reciprocating within the cylinder and a shock absorbing device arranged in the length of the rope 40 between the loop and resistance piston.

24. In apparatus for arresting aeroplanes the combination of a rope, a flexible aeroplane-engaging loop at one end of the rope, a sliding connection between the second end 45 of the rope and the first end portion adjacent to the loop, a landing surface, two pulleys spaced apart on axes disposed below the landing surface, the rope being led around one pulley along the landing surface and around the second pulley and thence back to the first pulley so that the ends of the rope with the flexible loop lie on the landing surface, means for preventing the rope being drawn away from the landing surface, means for exerting a pull upon the rope 50 in a direction parallel to its length and means for applying resistance to the travel thereof over the pulleys.

25. In apparatus for arresting aeroplanes 60 the combination of a rope adapted to travel in the direction of the aeroplane, means for applying resistance to such travel of the rope and a running noose on the free end of the rope adapted to be picked up by a portion 65 of the aeroplane and to close on said portion when engaged thereby.

In testimony whereof I have signed my name to this specification.

LOUIS JOHN LE MESURIER.
